UNITED STATES PATENT OFFICE.

JOSEPH VIERLING, OF PITTSBURGH, PENNSYLVANIA, ASSIGNOR TO PIONEER BRUSH WASHING MACHINE COMPANY, OF PITTSBURGH, PENNSYLVANIA, A CORPORATION OF DELAWARE.

WASHING-MACHINE.

1,360,060.

Specification of Letters Patent. Patented Nov. 23, 1920.

Application filed May 24, 1917. Serial No. 170,640.

To all whom it may concern:

Be it known that I, JOSEPH VIERLING, a citizen of the United States, residing at Pittsburgh, in the county of Allegheny and 5 State of Pennsylvania, have invented certain new and useful Improvements in Washing-Machines, of which the following is a specification.

My invention relates to improvements in 10 washing machines and more particularly to power driven brush washing machines including a rotatable brush and a scrubbing or backing roll resiliently mounted adjacent the brush and between which the articles to 15 be washed are passed.

Among the objects of the present invention are: to provide a construction by which the brush roll may be readily applied to and removed from the machine; to provide a 20 new and improved brush construction; to provide a new and improved scrubbing or backing roll; means for resiliently holding said roll against the brush, whereby articles varying in thickness may be passed between the brush and backing roll; means 25 for maintaining the backing roll out of engagement with the brush roll when the machine is not in use; adjustable clamping means for securing the machine to a tub or 30 other receptacle; and new and improved features of construction and combination of parts, all as hereinafter described.

In the accompanying drawings which illustrate an application of my invention,

35 Figure 1 is an elevational view showing one end of the apparatus and the manner of securing the same to the back of a wash tub or other receptacle.

Fig. 2 is a view similar to Fig. 1 taken at 40 the opposite end of the apparatus.

Fig. 3 is a horizontal sectional view taken on line 3—3 of Fig. 1.

Fig. 4 is a vertical sectional view taken on line 4—4 of Fig. 3.

45 Referring to the drawings, 1 designates a tub or receptacle having standards 2 and a cross-member 2^a adapted to have the washing machine clamped thereto. As illustrated and as preferred, the washing machine comprises a frame structure including end members or housings 3 and 4. These members 3 and 4 are tied together by means of a series of longitudinally extending rods 5, 6, 7 and 8 extending from one housing to the other.

For securing the washing machine to the tub 55 or receptacle, I provide a pair of adjustable clamp-members 9 adapted to be readily attached to and is engaged from the receptacle and the rods 7 and 8. This construction permits the clamps to be positioned at any 60 desired points between the housings. Both of the said clamp-members are of substantially the same construction and are formed with suitable bearing portions for the receptacle and the rods, and each is provided with 65 threaded members 10 and 11.

Characteristic and important features of the present invention are the brush-roll 12 and the manner of mounting said roll in the machine. As illustrated and as preferred, 70 brush-roll 12 is made up of a plurality of independent sections, each section having a key-way 13 adapted to engage with separate keys 14 located on the drive shaft 15. I find it of great advantage to make the brush-roll 75 in the manner illustrated, *i. e.*, made up of separate and independent sections adapted to be keyed to the drive shaft 15, for in thus doing so, I am enabled to interchange the 80 sections, prevent warping, and maintain the core or hub of the brush parallel or in alignment.

Shaft 15 has its ends journaled in journal-boxes 16, the latter being removably mounted in journal-box receiving openings 85 17 formed in the housings 3 and 4. Each of the journal-boxes is maintained within its opening by means of a screw 18 passed through an apertured lug 19 formed on the journal-box, said screw 18 having its inner 90 end located in a threaded hole formed in a face of the housing. 20 and 21 designate collars mounted on drive shaft 15 and designed to hold the brush sections against longitudinal movement on said shaft 15. 95 Collar 20 is internally threaded and adapted to engage threads 22 formed near one end of shaft 15. 23 indicate ball bearings for the shaft 15; the respective ends of shaft 15 project through said bearings and boxes, and as illustrated, have reduced end portions 24 and 25. End portion 25 has mounted thereon a drive pulley 26, said pulley being driven as shown by means of a belt 27 from a drive wheel 28 mounted on an electric motor shaft 29, the electric motor being diagrammatically indicated by the numeral 30. The opposite end of the drive shaft 15 or

the end 24 is provided with a pinion 31 provided for the purpose of actuating, in connection with drive belt 32 and pinion 33, a pump 34.

5 From the construction herein described and illustrated by the drawings, it will be understood that the shaft 15 together with its journal-boxes and the sectional rotary brush may be readily raised from the 10 housings for the purpose of removing the brush-sections or any of them, when so desired. This may be accomplished by loosening the screws 18 and lifting the brush-roll, etc., bodily from the housings. When free from 15 the housing, the pinion 31 together with one of the journal-boxes 16 is slid free of the shaft 15, then the collar 20 is removed, after which the brush-sections may be freed of the shaft.

20 Each of the housings 3 and 4 is provided with an outwardly extending arm or bracket 35 of similar construction, and each having an elongated slot 36 adapted to receive an end of a shaft 37 on which the sectional 25 scrubbing or backing roll 38 is mounted. This backing roll 38 is preferably made up of a series of independent circumferential sections loosely mounted on said shaft 37, and arranged to be independently rotated 30 by means of the brush roll.

The sectional backing roll 38 is resiliently held against the brush roll 12 by suitable means including a pair of bell crank levers 39, springs 40 and tension adjusting means 35 41. Each of the bell crank levers and its co-operating parts are independent of each other and act independently on the ends of the shaft 37, thereby permitting the sectional scrubbing or backing roll 38 or the end portions thereof to be moved independently and thus allow articles of varying thickness to be passed between the brush and backing roll without, however, substantially changing the uniform pressure at which the sectional 45 backing-roll is held against the brush-roll.

By making the scrubbing roll in the form of separate members or sections, and loosely mounting the same on shaft 37, I am enabled 50 to prevent the articles being washed from wrapping or twisting around the scrubbing roll.

In machines of this character it is important to keep the scrubbing roll out of contact with the brush-roll when the machine is not being used, and I have provided simple and efficient means for this purpose. As 55 illustrated, these means comprise a pair of pivoted arms 42, one located adjacent to each of the brackets 35, with each arm 42 having a finger 43. It will be understood 60 that as the shaft 37 is moved away from the brush-roll, this movement will cause the arms 42 to be raised sufficiently to permit 65 the shaft to pass under the said fingers 43

and after the shaft passes thereunder, the arms together with the fingers 43 are lowered with the fingers in engagement with the shaft, thereby preventing the shaft from moving toward the brush-roll until the fingers are released.

Motor 30 is supported on an adjustable plate 44, the latter being pivotally secured to a bracket 45 by means of a bolt 46. The forward end of plate 44 is provided with an 75 adjusting screw 47 entered in a threaded opening in said plate and adapted to make contact with a portion of the frame structure. The purpose of this construction is to enable the drive belt 27 to be properly adjusted, tightened or loosened as desired.

Water for washing from any suitable source of supply may be introduced to the tub through valve-controlled pipe 48 and pipe 49. After a sufficient quantity is supplied I maintain a continuous circulating system through pipe 49, pipe 50, pump 34, pipe 51, and the distributing pipe 52. Pipe 52 is supported from the frame-work by means of brackets 53 and is provided with 90 openings 54 through which streams or jets of water are projected downwardly upon the articles being washed.

What I claim is:—

1. In a washing machine and in combination, a frame, a rotatable drive shaft journaled in the frame, a brush structure carried by and rotatable with the shaft, a rod carried by and freely shiftable in said frame, a succession of roll sections extending longitudinally of and loosely mounted on said rod to permit individual movement of the sections, and means at the opposite ends of said rod for resiliently and yieldably supporting the rod, whereby said sections will accommodate for variations in washing conditions.

2. In a washing machine and in combination, a frame, a rotatable drive shaft journaled in the frame, a brush structure carried by and rotatable with the shaft, a rod carried by and freely shiftable in said frame, a succession of roll sections extending longitudinally of and loosely mounted on said rod to permit individual movement of the sections, and individual means at each end of the rod for normally maintaining said sections in a position of contact with the brush structure, said means including a pivoted bell crank lever, and a tension device adjustable to vary the general pressure of the rod.

3. In a washing machine and in combination, a frame having end members provided with open recesses, a rotatable drive shaft carrying journal boxes at its ends, said boxes being positionable within said recesses, means for removably securing said boxes in position, a brush structure carried by and rotatable with the shaft, said shaft brush

structure and its journal boxes forming a unit removable bodily, said end members also being slotted in a direction angular to the direction of positioning movement of the shaft, a rod loosely supported in said slots, a roll structure loosely mounted on said rod, and means for yieldably supporting said rod to normally maintain the roll structure in operative position relative to the brush structure.

4. In a washing machine and in combination, a frame, a rotatable drive shaft journaled in the frame, a brush structure carried by and rotatable with the shaft, a rod, carried by and freely shiftable in said frame, a scrubbing roll structure loosely mounted on said rod, individual yieldable

resiliently-supported mechanism at the opposite ends of the rod for normally maintaining said roll structure in a position of contact with the brush structure, and means operative at will for locating said rod in position to maintain said roll structure spaced from and out of contact with the brush structure, said means including a normally-inactive pivoted latching device at each end of the rod.

In testimony whereof I affix my signature in presence of two witnesses.

JOSEPH VIERLING.
